DESIGN FOR A TOKEN DISPENSER

Thomas G. Bogress, Kirksville, Mo.

Application April 11, 1938, Serial No. 76,438

Term of patent 7 years

To all whom it may concern:

Be it known that I, Thomas G. Bogress, a citizen of the United States, residing at Kirksville, in the county of Adair and State of Missouri, have invented a new, original, and ornamental Design for a Token Dispenser, of which the following is a specification, reference being had to the accompanying drawing, forming a part thereof.

Figure 1 is a perspective view of a token dispenser showing my new design.

Fig. 2 is a side elevation of the same; and,
Fig. 3 is an end elevation of the same.

I claim:

The ornamental design for a token dispenser,
as shown.

THOMAS G. BOGRESS.
